ELASTIC BULB FOR A MEDICINE DROPPER

Edmund A. Jones and Robert E. Karlson, Somerville, N.J., assignors to Ortho Pharmaceutical Corporation, a corporation of New Jersey

Filed Dec. 5, 1966, Ser. No. 4,917

Term of patent 14 years

(Cl. D83—1)

Fig. 1.

Fig. 2.

Fig. 3.

The broken lines are shown for purposes of illustration only.

We claim:

The ornamental design for an elastic bulb for a medicine dropper, as shown and described.
